JOHANN KUBLER, OF BADEN, SWITZERLAND, ASSIGNOR TO AKTIENGESELLSCHAFT
BROWN, BOVERI AND CIE., OF BADEN, SWITZERLAND.

TRANSFORMER OIL TANK.

Application filed October 5, 1922, Serial No. 592,643, and in Switzerland October 15, 1921.

It is known to cool the oil of transformer oil boxes by a system including radiators made up of cooling pockets mounted exteriorly on the walls of the transformer box 5 or tank and communicating at top and bottom with the interior of the oil box by means of short ducts. Such cooling pockets have been arranged hitherto either in large number side by side in the form of flat narrow structures of approximately lens-shaped cross-section, or in smaller number, down to two, in the form of flat pockets of corrugated sheet metal.

Those constructions have various drawbacks, of which may be mentioned, the hindrance to the access of air in the horizontal direction, the difficulty of cleaning and, sometimes, insufficient strength.

To avoid those drawbacks, according to 20 this invention, the cooling pockets are constructed of flat sheet metal plates, each adapted to cover a considerable portion of the adjacent wall of the tank, these pockets or plates being dished or flanged at their 25 edges and connected together in pairs in an oil-tight manner, and the several pockets being connected in communication with one another and the tank by means of flanges or bushings affixed to the plates about the communicating apertures in an oil-tight manner.

An embodiment of this invention is illustrated in the accompanying drawings in which:

Figure 1 is a diagrammatic vertical section of a transformer oil-box according to 35 this invention, the arrow line indicating the direction of the circulation of the oil.

Figure 2 is a horizontal section of the box.

Figures 3, 5 and 7 are detailed sectional 40 elevations showing methods of connecting the cooling pockets to the oil-box, and

Figures 4, 6 and 8 are the corresponding 45 detailed elevations of Figures 3, 5 and 7 respectively.

The nature of the invention will be ascertained from the illustrative example shown in the drawing. In this, the reference character *a* designates the transformer oil box or tank, the same having flanges *b* formed thereon by pressing, welding or riveting, at the desired locations and affording apertures for the passage of oil. The cooling pockets *c* are each composed of two sheet metal plates welded together at the edges

of their marginal flanges or dished portions *d*, whereby the parallel portions of the plates are spaced apart to afford thin oil circulating chambers of substantial area. These plates are provided with connecting flanges or bushings *e* which afford oil passages through the plates and reinforce the plates about such passages. The dimensions of these pocket members preferably are such that they cover substantially the area of the respective sides of the transformer tank to which they are to be connected, and the location of the flanges or bushings *e* is preferably such that the oil passages therethrough align with the oil passages through the passages *b* of the tank walls. The 55 pocket members as thus constructed are mounted on the tank by oil tight connections which perform the double function of supporting the pockets on the tank and affording communicating flow connections between the interior of the tank and the respective pocket members. The form of connections may be of any sort appropriate to accomplish these results.

As shown in Figs. 3 and 4, the flanges *e* are connected together in an oil-tight manner by means of right and left hand screw-threaded radiator nipples *f* with the interposition of packing or gaskets between the flanges of juxtaposed pocket members.

As shown in Figs. 5 and 6, a short piece of tube *g* is screwed, soldered or welded in each pair of oppositely situated flanges of one and the same pocket, and bolts *h* are inserted through the tube orifices of the several pockets, and by their means the flanges are pressed together in an oil-tight manner.

As shown in Figs. 7 and 8, the flanges *e* of each cooling pocket *c* are made in one piece, and are formed with radial apertures *i* 95 for the passage of the oil into the cooling pockets. The several cooling pockets are pressed together in an oil-tight manner against the flange *b* of the tank *a* by means of through bolts *h* with the interposition of 100 packing rings.

The outer closure of the oil passage aperture may be formed or constituted by a pocket which is provided with flanges *e* on one side only. A pocket of this kind would however be a separate construction and be capable neither of being changed nor removed nor extended. For this reason it is 105

preferred to construct all the pockets alike, and to close the outer aperture by means of a screw-on lid *m* or a bolted lid *n* as shown in the drawings.

5 In this fashion, as many as desired of the pocket members may be assembled in collateral relationship, extending parallel to the sides of the tanks, so that the entire assembly conforms in general to the contour and wall 10 dimensions of the tank. The flanges or bosses *e* constitute spacing members between juxtaposed pocket members, so that an intervening air circulation space is afforded, the width of which space may be governed 15 by the thickness of the gaskets inserted between the flanges of the juxtaposed pocket members. These air circulating spaces are open to the surrounding atmosphere at the top, bottom and ends of the pocket members, 20 so that free circulation of cooling air over the entire wall areas of the pocket members is permitted. By virtue of the communicating passages afforded through the connecting flanges, an automatic circulation of oil is 25 accommodated, from the top of the transformer tank into the upper portions of the pocket members, down through the pocket members as the oil cools, and back into the tank at the bottom. By virtue of the location 30 of the connections adjacent the corners of the pocket members, they are afforded very stable support on the tank, in spite of their extensive area, and, consequently, they may be formed of quite thin plates which 35 expedite the conduction of heat from the contained oil to the external air.

It will be observed, therefore, that the invention permits of a very material simplification in the construction of air cooled transformer containers, as any desired amount of 40 cooling surface may be provided by use of pocket members of a standardized construction. Thus a transformer tank of standardized size and construction may be equipped 45 to meet the requirements of any of different climatic conditions, a larger number of cooling pockets being employed if the apparatus

is to be installed in a hot climate, and a smaller number if for a cooler climate.

What I claim is:—

1. Apparatus of the class described comprising, in combination with an oil tank, a plurality of similar pocket members conforming approximately in area and contour with a wall of the tank, said pocket members being disposed in collateral relationship with one another and with said wall of the tank and being spaced from one another and from the tank wall to afford intervening air circulation spaces, means connecting said pocket members to one another and to the tank at distributed points adjacent their top and bottom margins, said tank and pocket members being provided with communicating passages in their upper and lower parts, and said intervening air spaces having communication with surrounding atmosphere at the margins of the pocket members.

2. In apparatus of the character described, a receptacle having fluid inlet and outlet openings, and a cooling unit disposed in proximity to a wall of said receptacle and providing with the latter by way of said openings a closed circulating circuit for fluid; said unit comprising a plurality of superimposed spaced radiating elements each comprising a pair of complementary plates fitted and secured together at their marginal portions and formed to provide a chamber forming part of such circuit, the plates being provided with flanged openings registering with each other and with one of said receptacle openings, and means extending through the flanges at the plate openings and into fastening relation with said receptacle wall at said receptacle opening and operating to hold said unit in assembled relation with respect to said receptacle and to hold said elements comprising said unit in assembled relation with respect to themselves.

In testimony whereof I have signed my name to this specification.

JOHANN KUBLER
